CLAIM

The ornamental design for a clothes pin, as shown and described.

DESCRIPTION

FIG. 1 is a front perspective view of my new design for a clothes pin;

FIG. 2 is a rear perspective view thereof;

FIG. 3 is a top plan view thereof, the bottom plan view being a mirror image thereof;

FIG. 4 is a right side elevation view thereof;

FIG. 5 is a left side elevation view thereof;

FIG. 6 is a front elevation view thereof; and,

FIG. 7 is a rear elevation view thereof.

The broken lines represent portions of the clothes pin that form no part of the claimed design.

MINKY is a Registered Trademark of Vale Mills Ltd.

1 Claim, 6 Drawing Sheets
